CHECK AND COUPONS

Odeon Lefebvre, New York, N. Y.

Application February 10, 1942, Serial No. 430,177

6 Claims. (CL. 283—60)

My invention relates to a check on which the orders are itemized and the quantity of each item indicated. Among the purposes and objects of my invention are to provide:

A check which prevents theft of food.

A waiter's check having duplicate and separable marginal tabs.

A device for quickly providing many varied duplicates.

A convenient safe device for dispensing supplies.

I accomplish these and other objects by the construction herein described and illustrated by the accompanying drawing forming a part of this disclosure in which the various figures are:

Fig. 1 is a plan view.

Fig. 2 is a fragmentary detail.

Fig. 3 is a fragmentary detail of a modification.

Fig. 4 is an enlarged detail of the tabs shown in Fig. 3.

Similar reference characters refer to similar parts throughout the several views of the drawing and in the specification to follow.

I am aware that the use of detachable tabs or coupons have been common for many purposes such as reminders, indexes, ballots, bonds, etc. The particular use of my coupons and their relation to other entries on my waiter's check result in only a use for detachable tabs or coupons but also result in a change of construction which at first glance appears similar to others but because it is a duplicate entry separated from entries of many other things, its construction and the new use accomplished by this novel combination is of great importance as will be seen by the disclosure of its application and operation which follows the specification of the construction.

Referring to the drawing, I have shown two of the numerous details of construction which are possible to carry out the underlying principles of my invention. I wish it understood that the precision of my disclosure in describing in detail these embodiments of my invention is not to be taken as limiting its scope but rather to make my invention better understood.

To those skilled in the art to which my invention pertains, it will be obvious after a study of this disclosure that many modifications may be made to suit my invention to its many uses.

My waiter's check 1, as typified by Fig. 1 of the drawing, has a serial number 2 shown at the top 3 above the horizontal lines 4 which separate the heading listings 5, such as the name of the hotel or club using my check and system to safe-

guard against loss of items 6 listed below the horizontal lines 4.

The lines 7 horizontally disposed on the body and extending beyond the vertical line of severance 8 where they also are severed, thereby forming coupons 9 on which are listed the same items as are listed on the conjoined or extension line 7. Each coupon is on the horizontal line having a like or duplicate item entry.

10 In Figs. 1 and 2, I have shown a box 10 on each coupon and another box 11 on the same line on which the quantity number of each item may be entered; thus, if one egg were ordered, the number 1 will appear in each box 10 and 11 and the item (egg) will appear in the coupon box 12 and also in the box 13 adjacent the box 11. Adjacent the box 13, I have provided the price boxes 14 and 15 for dollars and cents representing the charge for the items in the boxes on the same line 7 both on the coupon and the body of the check.

15 In Figs. 3 and 4, I have shown my check 21 as having the horizontal lines 27 on which the entries the items 26 may be placed in the same manner as the items are placed on the lines 7 of the check 1. The quantity box 30, however, is disposed so that one-half of the box is on the coupon, which is separated by the vertical line of severance 28 and the other half of the box 30 is on the body of the check. Thus, the number or quantity of each of the items may be entered but once yet it will not only appear on both the coupon but on the body of the check. The use of Roman numerals written so as to be severed by the removal of the coupon also adds further security against alterations of the numbers as they must match with the other half of the number when again placed in their original relationship, i. e.: as they were before being separated by removing the coupon.

20 In Fig. 2, I have shown the lines of severance as rows of perforations while in Figs. 3 and 4, the lines of severance are cuts 16 through the material leaving the bridges 17 to hold the coupon in place until the bridges are broken by tearing the coupon from its conjoined position of securement to the body of the check. When the cuts and bridges are disposed, as shown in Fig. 4, the corners 18 may be completely cut out so that the severance is more complete and thus more easily made. This arrangement of cuts and bridges is preferred when the material of my check is relatively stiff and the corners thus more difficult to tear away.

25 While I have shown the bridges 17 as disposed

midway between the corners 18 of each coupon, these bridges may be positioned so that each alternate coupon is entirely detached from the body of the check as at 22, or otherwise disposed provided the corners of the coupons are not attached to the check.

The top corners 19 are preferably rounded so that the checks may be quickly inserted into the waiter's uniform pocket. The bottom corners 20 may be square or slightly rounded.

The operation of my check and the system to which it is applicable is illustrated as follows:

The waiter is provided with checks having serial numbers 17640 to 17700 at the beginning of his shift at the hotel dining room; he takes the order of the guests at the table, calling for items of various kinds and in various quantities which after entering on the lines 1 or 21 which he receives from the chef, pantry man, pastries, bar, etc., each one of the stations and places where the items are obtained receive from him a coupon removed from his check listing the quantity and items he receives. Each of the items thus received is only obtainable by exchanging the coupon which is a receipt for the items. The checker looks at the check to see that the amounts charged and items listed have been exchanged for the coupons.

At the end of the shift, the pantry man, chef, bar, etc., must have coupons representing the items removed from their respective stock of supplies and the waiter must have delivered the items to the guest. The coupons and checks must also agree exactly.

Having thus disclosed and described in detail embodiments of my invention, what I claim to be my invention is set forth in the following appended claims.

I claim:

1. In a check having detachable coupons along its marginal edges, one of the coupons detachably secured to adjacent coupons and to the body of the check and bridges securing the coupons to each other and to the body of the check, said bridges being so disposed that the corner of each coupon adjacent said check is detached.
2. In a check, a row of detachable coupons positioned along a substantial part of one of the marginal edges of said check and bridges securing said coupons to each other and to said check,

said bridges being so disposed in relation to said check that all of the adjacent corners of said coupons are detached from said check when said coupons are secured thereto.

5. In a sheet having detachable coupons along its marginal edges, one of the coupons being detachably secured to adjacent coupons and to the body of the sheet and bridges securing the coupons to each other and to the body of the sheet, said bridges being so disposed that the corner of each coupon adjacent the body of the sheet is detached.

15. In a sheet having detachable coupons along its marginal edges, one of the coupons being detachably secured to adjacent coupons and to the body of the sheet and bridges securing the coupons to each other and to the body of the sheet, said bridges being so disposed that the corner of each coupon adjacent the body of the sheet is detached, the spaces between said bridges comprising a plurality of slits, said slits at the corner juncture of said coupons being joined to provide a cut out corner.

25. In a sheet having detachable coupons along its marginal edges, one of the coupons being detachably secured to adjacent coupons and to the body of the sheet and bridges securing the coupons to each other and to the body of the sheet, said bridges being so disposed that the corner of each coupon adjacent the body of the sheet is detached, the spaces between said bridges comprising a plurality of slotted scores, said slotted scores at the adjacent corners of said coupons being joined to permit the coupons to be detached without tearing the corners.

35. In a sheet having detachable coupons along its marginal edges, one of the coupons being detachably secured to adjacent coupons and to the body of the sheet and bridges securing the coupons to each other and to the body of the sheet, said bridges being so disposed that the corner of each coupon adjacent the body of the sheet is detached, the spaces between said bridges comprising a plurality of slotted scores, said slotted scores at the adjacent corners of said coupons being joined to permit the coupons to be detached without tearing the corners, and the adjacent body of the sheet.

ODELON LEFEBVRE.
